C. E. LAMBURTH.
REINFORCED CONCRETE PILE FOR PIER AND FOUNDATION CONSTRUCTION.
APPLICATION FILED OCT. 22, 1908.

UNITED STATES PATENT OFFICE.

CASSIUS E. LAMBURTH, OF SAN FRANCISCO, CALIFORNIA.

REINFORCED-CONCRETE PILE FOR PIER AND FOUNDATION CONSTRUCTION.

941,078.

Specification of Letters Patent.

Patented Nov. 23, 1909.

Application filed October 22, 1908. Serial No. 458,967.

To all whom it may concern:

Be it known that I, CASSIUS E. LAMBURTH, a citizen of the United States, residing at the city and county of San Francisco and 5 State of California, have invented new and useful Improvements in Reinforced - Concrete Piles for Pier and Foundation Construction, of which the following is a specification.

10 My invention relates to reinforced concrete piles for pier and foundation construction.

The object of the invention is to devise a simple, practical, and comparatively cheap 15 system of piles for pier and foundation construction, together with means for placing and anchoring these concrete piles.

10 My invention consists of the parts and the construction and combination of parts as hereinafter more fully described and claimed, having reference to the accompanying drawings, in which—

Figure 1 is a section of the invention. Fig. 2 is a detail of top cap, (elevation). 25 Fig. 3 is a plan of same. Fig. 4 is a detail of bottom cap (elevation). Fig. 5 is a section on line $y-y$. Fig. 6 is a section on line $x-x$. Fig. 7 is an enlarged broken sectional view of a portion of the pile showing the 30 concrete removed from parts of the reinforcing members.

A represents one of my reinforced concrete piles which may be of any length, shape or diameter, with a central opening 2 35 extending lengthwise through it from end to end. The pile is preferably rectangular in cross-section and tapered lengthwise, with the lower end of the pile provided with a base-plate 3 corresponding in exterior out- 40 line to the lower end of the pile, and having a central opening corresponding to the opening 2 in the pile and designed to accommodate the pipe 4; which latter forms the walls of the opening 2.

45 The base-plate 3 has a central downwardly extending flange 5 projecting below the lower end of the plate with reinforcing ribs 6 at suitable intervals. These ribs 6 at the corners are made with suitable seats 50 7 and are cored out to pass the reinforcing rods or bars 8 which extend lengthwise through the body of the pile. Nuts 9 screw on to the lower ends of these rods and seat on the seats 7.

55 In the making up of the pile proper, any suitable form of a mold is employed, and

in this mold a skeleton reinforcing framework is set up consisting of the bars 8, intermediate longitudinally-extending bars 10 and the central pipe 4.

Around the bars 10 a suitable wire fabric 60 11 is wound, including, as here shown, a rectangular area outside of the pipe 2. A second and similar wire fabric 12 is wrapped around the outer series of bars 8, and then 65 all these bars and the pipe 4 are firmly embedded in a packing of cement or concrete which when allowed to set forms a monolithic column of great strength and rigidity. Preferably the two wire fabric cylinders 70 11-12 are arranged one within the other and diagonally of each other, as shown, for the purpose of giving greater strength.

When the pile is ready to be placed in position, it is lowered into the mud or sand, as the case may be, and then boring and pumping tools of suitable description are sent down through the opening 2 to remove the mud, sand, or rock; the pile sinking, or 80 being forced down as the material below the pile is taken out. Any suitable means, not necessary here to be shown, may be employed to place or force the pile downward to a sufficient distance. If desired, a wooden 85 pile having a diameter sufficient to allow it to pass down through the central opening 2 of my hollow concrete pile may then be inserted into this concrete pile and driven down into the mud or earth beneath, as represented at 14, leaving any desired portion of the wooden pile sticking up into the concrete pile, and thus affording a substantial anchorage for the same. The space on top of the wooden pile is then filled with concrete, as represented at 15. Under some 90 circumstances, a wooden pile may be first driven down and then my concrete pile slipped down over it; the space on top of the wooden pile then being filled with concrete. Under some circumstances, the 95 wooden pile anchorage may be entirely dispensed with, in which case my concrete pile, after being forced or sunk to a suitable depth to sustain the load, is filled with concrete.

When the pile is placed, and the hollow portion of it filled with concrete, or other suitable material, the top of the pile is crowned with a suitable metal cap, as represented at 16. This cap or crown plate 110 preferably has an inside circular flange 17

to fit inside the hollow concrete pile, and a cap 18 of a size approximately that of the top of the pile. This cap plate 18 preferably comprises two plates suitably spaced 5 by the webs 19, with a central opening 20 extending through the plates, through which concrete may be poured into the top of the pile to fill any remaining space therein. On top of the crown plate 16 are laid the beams, 10 and fastened thereto by suitable means; and any form of flooring or superstructure may be placed on these beams.

Since these piles are comparatively cheap to manufacture and easily handled, as compared with the usual concrete piers, any desired number of them may be used in the construction of piers, or as a foundation, and they may be placed as closely together, or as far apart, as desired or needed. The 20 pile is, moreover, indestructible by marine insects, decay, or fire.

These piles are so long and heavy, that under some circumstances, to enable them to be safely handled, and for other reasons, it 25 is desired to make them rectangular in cross-section at the ends, and to give the two opposite narrower sides a bulge or swell between the ends, as shown in Figs. 1 and 6; the additional body of concrete afforded by 30 this bulge or swell giving additional strength at the center of the pile. At the same time, making the pile rectangular in cross-section and giving it this additional swell in the manner described, allows the piles to be set 35 and braced in forming a pier or foundation construction, in a much more substantial manner than by the use of square piles or round piles; since the diagonal brace piles may be laid against the flat, wide sides of 40 my improved piles and secured thereto to best advantage.

Having thus described my invention, what I claim and desire to secure by Letters Patent is—

45 1. A concrete pile having an axial opening through it, lengthwise extending reinforcing rods embedded in the body of the concrete between said central opening and the outer wall of the pile, a metal tube em-

bedded in the concrete interior to said rods 50 and forming the wall of said axial opening, and two cylinders of wire fabric embedded in the body of concrete and passing around the exterior of the rods, the fabric cylinders engaging alternate rods whereby one cylinder 55 is arranged within the other and the sides of one cylinder are diagonal to the sides of the other cylinder.

2. In a hollow reinforced concrete pile comprising a body of concrete having a central opening extending from end to end, metal reinforcing members arranged longitudinally of the pile and wire fabric cylinders surrounding said members, a base plate 60 upon which the lower end of the pile rests, 65 said base plate having a downwardly extending flange with reinforcing ribs at intervals forming seats for the reinforcing members, certain of said members extending through said ribs, and means for fastening 70 the ends of said members to the base plate.

3. In a hollow reinforced concrete pile comprising a body of concrete having a central opening extending from end to end, metal reinforcing members arranged longitudinally of the pile and wire fabric cylinders surrounding said members, a base plate 75 upon which the lower end of the pile rests, said base plate having a downwardly extending flange with reinforcing ribs at intervals forming seats for the reinforcing members, certain of said members extending through said ribs, means for fastening the 80 ends of said members to the base plate, and a cap plate of metal fitting on top of the pile 85 and having a central opening to register with the opening through the pile and adapted to admit a filling of concrete to close the central opening of said pile, said cap plate having an inside flange adapted to enter the 90 top of the central opening of the pile.

In testimony whereof I have hereunto set my hand in presence of two subscribing witnesses.

CASSIUS E. LAMBURTH.
